WASHING APPARATUS

Earl K. Clark and Frank Breckenridge, Mansfield, Ohio, assignors to Westinghouse Electric & Manufacturing Company, East Pittsburgh, Pa., a corporation of Pennsylvania

Application August 30, 1938, Serial No. 227,457

6 Claims. (Cl. 141—9)

Our invention relates to washing apparatus and has for an object to provide improved apparatus of this kind.

A further object of the invention is to provide improved washing apparatus wherein a predetermined quantity of water is admitted to the washing chamber for washing and rinsing operations.

It is a further object of the invention to admit a measured quantity of water to a washing mechanism for washing and rinsing operations and to heat the water for one or more of the operations.

It is another object of our invention to provide an improved machine for washing tableware or the like wherein the admission of water and a detergent, the discharge of the vitiated water and the washing of the tableware are automatically controlled in accordance with a predetermined program for effecting the washing and rinsing of the tableware.

These and other objects are effected by our invention as will be apparent from the following description and claims taken in connection with the accompanying drawing forming a part of this application in which:

Fig. 1 is a diagrammatic view of a dishwashing machine constructed and arranged in accordance with our invention; and,

Fig. 2 is a diagram of the electrical connections between the various electrically operated devices shown in Fig. 1.

In the accompanying drawing and description which follows, our invention is disclosed as applied to a dish washing machine but it will be understood that it is equally applicable to various other forms of washing machines. As shown in Fig. 1, which is diagrammatic for the sake of clearness, the washing apparatus includes a casing structure 10 that defines a washing chamber 11, provided with an access opening 12 and closed by a suitable closure 13. A rack structure 14 is disposed within the chamber 11 for supporting the tableware to be washed, which tableware is shown as a plurality of dishes 15. Water is admitted to the washing chamber 11 for washing and rinsing operations from a suitable source through a conduit 16 under control of a measuring mechanism, generally indicated at 17 and described more in detail hereinafter.

Any suitable mechanism may be employed for washing the dishes 15 but, as shown, a rotating impeller 18 disposed in the bottom of the chamber 11 is employed. The impeller 18 projects the washing and rinsing water in contact with the dishes 15 at high velocity for washing the same

in a well-understood manner. The impeller 18 is driven by a suitable electric motor 19 disposed exteriorly of the chamber 11.

Vitiated water is discharged from the chamber 11 through a drain pipe 21 having a suitable valve structure 22 connected therein. As shown, the valve 22 is of the solenoid-operated type and includes an operating coil 23. As the construction and operation of solenoid-operated valves are well known in the art, no further description of the valve 22 is deemed necessary other than to state that it is open when the coil 23 is energized and, conversely, it is closed when the coil is deenergized. A mechanism, generally shown at 24 and described in detail hereinafter, is employed for depositing a predetermined amount of detergent material such as, for example, powdered soap in the chamber 11.

In accordance with our invention, the admission and discharge of water, the admission of soap to the chamber 11 and the operation of the impeller 18 are automatically controlled in accordance with a predetermined program. To this end, a control device or timing mechanism, generally shown at 25, is employed for sequentially actuating the various elements for effecting these operations. The timing mechanism 25 is preferably carried by the casing 10 in a position convenient to the operator and is shown diagrammatically in Fig. 2, further reference to which will be made hereinafter.

Reference will now be had to the water measuring device 17. This device includes a measuring tank 26 of predetermined volume for receiving water conveyed by the supply conduit 16, the flow of which is controlled by a solenoid valve 27 having an operating coil 28. The upper end of the tank 26 is open and the bottom of the tank is connected by means of a flexible conduit 29 with the chamber 11, the flow of water through the conduit 29 being controlled by a valve 31 having an operating coil 32. The electrically operated valves 27 and 31 are of the same general type as the valve 22 and operate in a similar manner.

The tank 26 is supported by a pair of bell crank levers 33 and 34 which are pivotally carried at 35 and 36, respectively, by the casing structure 10. The bell cranks 33 and 34 include opposed arms 37 and 38, respectively, having a compression spring 39 disposed between the ends thereof. The bias of the spring 39 determines the amount or weight of water that is delivered to the washing chamber 11 and is preferably adjustable. To this end, an adjustable member 40 is disposed

between the spring 39 and the arm 38. As shown, the member 40 is movable with respect to the arm 38 and is clamped thereto by a bolt 41 when adjusted to its proper position. A second spring 42 biases the tank 26 to its upper position at all times and elevates the tank when a predetermined weight of water is delivered therefrom.

In the position shown, the tank is in its elevated position and the springs 39 and 42 assist each other. When a predetermined weight of water is admitted to the tank 26, downward movement is effected against the bias of the springs. As the arms 37 and 38 move toward alignment, the effectiveness of the spring 39 in resisting movement thereof is progressively reduced so that the tank 26 is moved in a snap acting manner to its lower position. It will be apparent that downward movement of the tank 26 is assisted by the spring 39 after the arms 37 and 38 pass their aligned or "dead center" position.

In the lower position of the tank 26, the springs 39 and 42 oppose each other. It will be understood that the bias of the spring 42 is sufficient to overcome the bias of the spring 39 and the weight of the movable tank 26 so that after a predetermined weight of water is discharged from the tank 26, it is moved to its elevated position, as shown by the spring 42. Snap acting movement of the tank 26 as it moves upwardly is effected by the spring 39 in the manner described heretofore. Preferably, the effectiveness of the spring 42 in biasing the tank 26 upwardly is adjustable. To this end, the lower end of the spring 42 is secured to the bell crank 34 at different distances from its pivot 36 by means of a clamping bolt 42a adjustable in a slot 42b formed in the bell crank 34.

Heating of the water in the tank 26 is effected in any suitable manner and, preferably, by an electric heating element 43 under control of a conventional thermostat, shown at 44. Energization of the heating element 43 is also controlled by a switch 45 having a stationary contact 46 and a movable contact 47 associated with a movable element of the measuring mechanism 17 such as, for example, the bell crank 34. The switch 45 is closed when the tank 26 is in its lower position and open when in its elevated position, whereby energization of the heater 43 can only be effected when water is contained in the tank 26.

A second switch structure 48 is actuated by the movable element of the mechanism 17, such as, for example, by the bell crank 33. The switch 48 includes a movable contact 49 that engages stationary contacts 51 and 52, when the tank is in its elevated and lower positions, respectively. The switch 48 is of the double throw type and controls energization of the water valve solenoids 28 and 32 as shown in Fig. 2, further reference to this control being made hereinafter.

The device 24 for depositing detergent in the chamber 11 may be of any suitable construction and, as shown, includes a magazine or hopper 53 for the detergent and having a discharge opening 54 formed in the bottom thereof. A movable member including a pair of spaced walls 55 effects the delivery of powdered soap to the washing chamber 11. The spaced walls 55 are carried by a stem 55a and define a chamber 56 therebetween which chamber registers with the opening 54 in the position of the device shown for receiving soap that gravitates from the hopper 53. The spaced walls 55 and the soap in

the chamber 56 are moved to the left by a magnet 57 having an operating coil 58 when the latter is energized. In this position, the chamber 56 registers with a passage 59 communicating with the washing chamber 11, so that the soap gravitates from the chamber 56 through the passage 59 to the washing chamber 11. A spring 61 returns the walls 55 to the position shown when the magnet coil 58 is deenergized, whereby soap gravitates from the hopper 53 to the chamber 56 for delivery to the washing chamber 11 the next time the magnet is energized. Preferably, the amount of soap delivered to the chamber 11 is adjustable in order that the most desirable washing solution may be obtained with the water available. As shown, one of the walls 55 is threaded at 55b to the stem 55a so that it may be adjusted longitudinally of the stem 55a for varying the capacity of the chamber 56. The detergent depositing device 24 is shown by way of example and it will be understood that other suitable mechanisms may be employed for depositing a detergent in liquid or granular form in the washing chamber.

The various electrically operated elements referred to heretofore are controlled by the timing device 25 for effecting a predetermined program of steps in the washing and rinsing of the dishes. The timing device 25 preferably includes a rotatable drum 65 which is diagrammatically shown in development in Fig. 2 and movable in the direction of the arrow. The rotatable drum 65 carries a plurality of electrically connected segments 66 to 76, inclusive, that cooperate with a plurality of stationary contact fingers 77 to 86, inclusive. The drum 65 is rotated by a motor 85 of the type commonly employed in the operation of electric clocks. A speed-reducing mechanism 86 is interposed between the motor and the drum 65 so that the latter is driven at a relatively low speed of, for example, 1/15 R. P. M. A slip clutch, diagrammatically shown at 87, is connected between the speed-reducing mechanism 86 and the drum 65 for permitting manual rotation of the drum 65 when initiating operation of the apparatus. A handle 88 is provided for the operator for manually rotating the drum 65. During operation of the motor 85, the drum 65 is driven through the clutch 87. In manually initiating operation of the apparatus, the drum 65 is rotated by the handle 88 until the contact segment 66 bridges the fingers 77 and 78 at which time the motor 85 is energized for rotating the drum 65.

The source of power for the various electrical elements is represented by line conductors L₁ and L₂. The contact finger 78 is connected to the line conductor L₁ so that when it is in engagement with the segment 66 all of the segments 66 to 76, inclusive, are of the same polarity as the line conductor L₁. The contact 77 is connected to one terminal of the timer motor 85, the opposite terminal of which connects with the line conductor L₂. The contact finger 79 is connected to one terminal of the heater 43, the opposite terminal of which is connected to the line conductor L₂ through the switch 45 and the thermostat 44. The contact fingers 80 to 84, inclusive, are respectively connected to terminals of the operating coils 58, 23, 32 and 28 and the motor 19. The opposite terminals of the coils 58, 23 and motor 19 are connected to the line conductor L₂. The opposite terminals of the coils 32 and 28 are respectively connected to the stationary contacts 52 and 51 of the switch structure 48. The

movable contact 49 of the switch 48 cooperates with the stationary contacts 52 and 51 and is directly connected to the line conductor L2. As the switch 48 is of the double throw type, it will be apparent that one or the other of the coils 32 and 28 is connected to the line conductor L2 at all times.

As energization of the heater 43 and the valve operating coils 32 and 28 is controlled by switching means other than the timing device 25, I have shown broken lines beside the movable segments 66 to 76, inclusive, which lines indicate the duration of periods of energization of the elements controlled by the segments. For example, the segment 75 engages the finger 83 continuously for a period of approximately nine minutes as indicated by the indicia at the right of the drum 65 but energization of the operating coil 28 is only effected during the three periods indicated by the broken lines beside the segment 75 or during periods when the movable contact 49 of the switch 48 engages its stationary contact 51. When the movable contact 49 disengages the contact 51, the circuit through the coil 28 is broken so that the portion of the segment 75 in engagement with the finger 83 at this time is not accompanied by a broken line. This method of illustration facilitates description of the operation of the apparatus as will be apparent hereinafter. As the motors 19 and 85 and the coils 58 and 23 are controlled solely by the timing device 25, the broken lines associated with their respective segments 76, 66, 68 and 69 to 71, inclusive, are coextensive therewith.

Operation

In operating the washing apparatus, the dishes 15 are first placed on the supporting structure 14 through the access opening 12, after which the door 13 is closed. The drum 65 of the timing mechanism 25 is then manually actuated to starting position wherein the segment 66 bridges the fingers 77 and 78. Accordingly, the circuit for the motor 85 is established and rotation of the drum 65 is started. During the starting operation, the contact segment 75 engages the contact finger 83 so that the operating coil 28 of the valve 27 is energized and admission of water to the tank 26 is effected. It is to be understood that during starting, the tank 26 is substantially devoid of water so that it is in its elevated position wherein the contact 49 engages the contact 51.

During the filling of the tank 26, contact segments 72 and 76 engage the respective fingers 82 and 84 whereupon the main motor 19 is energized and the circuit including the operating coil 32 conditioned for energization. Energization of the coil 32 is effected when a predetermined weight of water is admitted to the tank 26 for moving it to its lowermost position whereupon the contact 49 is moved into engagement with the contact 52. This operation of the switch 48 deenergizes the solenoid 28 and delivery of water to the tank 26 is terminated. The water flows from the tank 26 through the open valve 31 and is projected over the dishes 15 by the impeller 18. Accordingly, loose food particles are removed from the dishes and are entrained in the water in the chamber 11.

When a substantial portion of the water has been discharged from the tank 26, it is moved upwardly as described heretofore so that the operating coil 32 is deenergized and the coil 28 energized. Accordingly, water is again ad-

mitted to the tank 26 until it moves to its lower position, at which time the contact 49 engages the contact 52 and the switch 45 is closed. At this time the drum 65 is in the position indicated by the three-minute position on the scale so that the circuit is completed to the heater 43 through the segment 67 and finger 79. As the heater is energized, heating of the water admitted to the tank 26 is effected under control of the thermostat 44. The cold or first charge of water admitted to the chamber 11 has been projected over the dishes by the impeller 18 during the periods defined by the one to four minute positions on the scale. At approximately the four-minute position on the scale, the segment 69 engages the finger 81 for energizing the operating coil 23 of the discharge valve 22. Vitiated water with the entrained food particles is, therefore, discharged to the drain pipe 21 through the open discharge valve 22.

The next step in the cycle includes the closing of the drain valve 22 which is effected when the segment 69 is disengaged from the finger 81. With this operation, the segment 73 engages the contact 82 and, as the contact 49 is in engagement with the contact 52, the operating coil 32 of the valve 31 is energized and the heated water is discharged to the chamber 11. When the heated water has been discharged from the tank 26, upward movement of the latter effects closing of the contacts 49 and 51 so that a third charge of water is admitted to the tank 26. Furthermore, upward movement of the tank 26 opens the switch 45 for deenergizing the heater 43 and opens the circuit of the operating coil 32 of the water valve 31 as described heretofore. When the tank 26 is moved downwardly by the charge of water therein, the heater is energized by the closing of the switch 45 and the supply of water to the tank 26 is terminated. Closing of the contacts 49 and 52 conditions the coil 32 for energization, which is later effected by the engagement of segment 74 and finger 82.

During the period of filling the tank with the third charge of water, the segment 68 engages the contact finger 80 so that the operating coil 58 of the soap dispenser 24 is energized and a predetermined quantity of soap is admitted to the chamber 11. Washing of the dishes in the heated soapy water is now effected and continues until the contact segment 70 engages the finger 81 whereupon energization of the operating coil 23 is effected for opening the discharge valve 22. The water is completely discharged from the chamber 11 when the contact segment 70 disengages the finger 81 at which time the discharge valve 22 is closed. The valve 31 is again opened by energization of its operating coil 32 which is effected when the contact segment 74 engages the finger 82, it being understood that the tank 22 is in its lowermost position in which the movable contact 49 engages the stationary contact 52. Accordingly, the heated third charge of water is discharged to the chamber 11 for rinsing purposes. With the opening of the valve 31, the segment 67 disengages the finger 79 so that the heater 43 is rendered inactive. Admission of water to the tank 26 when it moves upwardly after discharging the third charge of water is prevented as the segment 75 is disengaged from the finger 83 and, therefore, the operating coil 28 of the admission valve 27 is incapable of energization.

The heated rinsing water is projected over the dishes by the impeller 18 until the water is dis-

charged from the chamber 11 which operation is effected by the engagement of the segment 71 with the contact finger 81 and the energization of the discharge valve operating coil 22. Continued operation of the motor 88 moves the drum 85 to the "off" position as shown in the drawings, at which time all of the elements of the washing apparatus are rendered inactive. A complete cycle of operation has now been described.

It will be apparent from the foregoing description that a uniform quantity of water is admitted to the washer by the measuring device 17 during each operation of the water admitting means regardless of any condition which tends to vary the amount of water delivered, such as for example, pressure changes in the water supply conduit. This is desirable for the most efficient operation of the impeller in projecting the wash and rinse water over the dishes. Furthermore, as the amounts of water and soap admitted to the washing chamber are fixed, the most effective washing solution is employed at all times. The embodiment of the measuring device 17 which we have shown measures the amount of water by weight but it is to be understood that our invention is not so limited and contemplates other methods of metering predetermined quantities of water to the washer.

Furthermore, our invention contemplates selectively supplying the water to the washing chamber in a heated or unheated condition. Supplying of water to the washer, discharging of the vitiated water therefrom, depositing a detergent in the washer and operation of the washing apparatus are automatically effected to provide a predetermined program of washing and rinsing steps in accordance with our invention, which program may be varied as desired.

While we have shown our invention in but one form, it will be obvious to those skilled in the art that it is not so limited, but is susceptible of various changes and modifications without departing from the spirit thereof, and we desire, therefore, that only such limitations shall be placed thereupon as are imposed by the prior art or as are specifically set forth in the appended claims.

What I claim is:

1. In apparatus for admitting water to a washing machine having a water-containing washing chamber, the combination of a measuring device for the water, a valve for controlling the admission of water to said device, a second valve for controlling the delivery of water from the device to said washing chamber, means responsive to the amount of water in said device for controlling said valves and effective to close said first valve when a predetermined amount of water is contained within the measuring device and to condition said first valve for operation to admit water to the device at other times, said means being effective to condition said second valve for operation to deliver water to the washing chamber when a predetermined amount of water is contained within the measuring device and to close said second valve at other times, and other control means for selectively opening said valves during the periods when the valves are conditioned for operation by the first-mentioned control means.

2. In apparatus for admitting measured quantities of water to a washing machine having a water-containing washing chamber, the combination of a tank, a valve for controlling the admission of water to said tank, a second valve for controlling delivery of water from the tank to

the washing chamber, said tank being disposed in an elevated position when substantially devoid of water and movable to a lower position when containing a predetermined weight of water, means responsive to the position of the tank for controlling said valves so that said first valve is closed during periods when the tank is in its lower position and is conditioned for operation to admit water to the tank in the elevated position of the tank, said controlling means conditioning said second valve for operation to deliver water to the washing chamber during periods when the tank is in its lower position and for closing the second valve in the elevated position of the tank, and other control means for selectively opening said valves during the periods when the valves are conditioned for operation.

3. In apparatus for admitting measured quantities of water to a washing machine having a washing chamber, the combination of a container for the water, an electrically operated valve for controlling the admission of water to said container, a second electrically operated valve for controlling the delivery of water from the container to the washing chamber, first and second switches for respectively controlling the energization of said valves, means responsive to the amount of water in said container for operating said switches so that the first switch is closed when the container is substantially devoid of water and opened in response to a predetermined amount of water in the container and so that said second switch is closed in response to a predetermined amount of water in the container and opened at other times, first and second master switches electrically connected to said first and second switches, respectively said master switches being active to control energization of the first and second electrically operated valves only during periods when their respective first and second switches are closed, and means for opening and closing said master switches in a predetermined sequence.

4. In apparatus for admitting measured quantities of water to a washing machine having a water-containing washing chamber, the combination of a measuring device for the water, a valve for controlling the admission of water to the measuring device, a second valve for controlling the delivery of water from the measuring device to the washing chamber, means responsive to the amount of water in the measuring device for controlling said valves and effective to close said first valve when a predetermined amount of water is contained in the measuring device and to condition the first valve for operation to admit water to the measuring device at other times, said means being effective to condition said second valve for operation to deliver water to the washing chamber when a predetermined amount of water is contained within the measuring device and to close the second valve at other times, means for heating the water in the measuring device, means effective during periods when the said predetermined amount of water is contained within the measuring device for conditioning the heating means for energization, means for selectively opening said valves during the periods when the valves are conditioned for operation by the controlling means, and means for controlling the energization of the heating means during periods when it is conditioned for operation.

5. In apparatus for admitting measured quantities of water to a washing machine having a

titles of water to a washing machine, the combination of a container for the water, an electrically-operated valve for controlling the admission of water to the container, a second electrically-operated valve for controlling the delivery of water from the container to the washing machine, a switch for controlling the energization of said first electrically-operated valve and closed when said container is substantially devoid of water and open when the container contains a predetermined amount of water, a second switch for controlling the operation of said second electrically-operated valve and open when the container is substantially devoid of water and closed when said container contains said predetermined amount of water, first and second master switches connected in series with said first and second-mentioned switches, respectively, and means for opening and closing said master switches in a predetermined sequence and for predetermined periods of time.

6. In apparatus for admitting measured quantities of water to a washing machine, the combination of a container for the water, an electrically-operated valve for controlling the admission of water to the container, a second electrically-operated valve for controlling the delivery of water from the container to the washing machine, a switch for controlling the energization of said first electrically-operated valve and closed when said container is substantially devoid of water and open when the container contains a predetermined amount of water, a second switch for controlling the operation of said second electrically-operated valve and open when the container is substantially devoid of water and closed when said container contains said predetermined amount of water, first and second master switches connected in series with said first and second-mentioned switches, respectively, and means for opening and closing said master switches in a predetermined sequence and for predetermined periods of time.

5 cally-operated valve for controlling the delivery of water from the container to the washing machine, a switch for controlling the energization of said first electrically-operated valve, said switch being closed when said container is substantially devoid of water and open when the container contains a predetermined amount of water, a second switch for controlling the operation of said second electrically-operated valve, said second switch being open when the container is substantially devoid of water and closed when said container contains said predetermined amount of water, a heater for heating the water in the container, a third switch for controlling energization of the heater, said third switch being open when the container is substantially devoid of water and closed when the container contains said predetermined amount of water, and a plurality of master switches connected in series with the respective first, second and third switches, said master switches being opened and closed sequentially and for predetermined periods of time.

EARL K. CLARK.
FRANK BRECKENRIDGE.
